(57) **CLAIM**

The ornamental design for a flexible kitchen countertop playset, as shown and described herein.

DESCRIPTION

FIG. 1 is a front perspective view of my flexible kitchen countertop playset;

FIG. 2 is a front view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines in the figures represent portions of the flexible kitchen countertop playset that form no part of the claimed design.

1 Claim, 6 Drawing Sheets
